DISPENSING DEVICE

Filed June 27, 1929

UNITED STATES PATENT OFFICE

LAURITZ MARTIN NARBO, OF BROOKLYN, NEW YORK

DISPENSING DEVICE

Application filed June 27, 1929. Serial No. 374,128.

This invention relates generally to dispensing devices, and refers more particularly to devices which are principally designed for facilitating the pouring of liquid fuel, such as gasoline from sealed containers into the fuel tanks of motor vehicles.

The invention broadly aims to provide an improved dispensing device which serves to simultaneously form an opening in a sealed container and to establish a fluid tight connection with the opening thus formed, to permit the contents thereof to be poured therefrom into a tank or other receiver.

It has been observed that considerable difficulty is encountered in pouring gasoline or other liquid fuels from five-gallon cans or other similar containers into the fuel tanks of motor vehicles, due to the difficulty of disposing the usual pouring spouts in close proximity to the filling opening of the tank, and the present invention, therefore, comprehends a dispensing device which includes a flexible tubular section, such as a length of hose provided with a rigid tubular section at one end thereof which is so constructed as to afford means for readily piercing a sealed container to form an opening therein for discharging the contents therefrom through the flexible section, which latter section may be introduced into the filling opening of the fuel tank.

As a further object, the invention contemplates in a dispensing device of the character set forth, a rigid tubular section which in addition to forming a discharge opening in a sealed container, serves to establish a fluid tight seal to insure against leakage of the contents during the pouring operation.

A further feature of the invention resides in the use of the free end of the flexible section of the device as a sheath to cover and protect the pointed or sharpened end of the rigid section to prevent injury to the person of the user, dulling of the cutting edges of the rigid section and the entrance of dust, dirt or other foreign matter to the interior of the sections.

Other objects of the invention reside in

the simplicity of construction and mode of use of the device, the economy with which it may be produced and the general efficiency derived therefrom.

With the above recited and other objects in view, reference is had to the following description and accompanying drawings, in which there is exhibited one example or embodiment of the invention, while the claims define the actual scope of the same.

In the drawings:

Figure 1 is a perspective view illustrating the device in juxtaposition to a sealed container.

Figure 2 is a fragmentary sectional view illustrating the device forced into the container and operatively associated therewith for dispensing the contents.

Figure 3 is a fragmentary view illustrating the device applied to the container and in dispensing position.

Figure 4 is a transverse sectional view taken approximately on the line 4-4 of Figure 2.

Figure 5 is a side view of the device partly in section and illustrating the manner in which the free end of the flexible section covers and protects the rigid section.

Figure 6 is a fragmentary sectional view through the dispensing device in pouring position, particularly illustrating the venting means.

Referring to the drawings by characters of reference, the dispensing device or spout designated generally by the reference character A, is designed to be associated with a sealed container, such as a can B, as illustrated, for the purpose of gravitationally dispensing the contents therefrom and pouring the same into the filling opening C of a receiver D. At the present time, containers or cans B such as illustrated are usually provided with a spout constituting a part of and sold and packaged with the container or can. These spouts are objectionable for many reasons, principally due to the fact that they occupy considerable space in the storage and shipment of the cans. By providing a dispensing device in accordance with the present invention, it is, therefore,

apparent that the usual spout will be dispensed with and the purchasers of the cans or containers will be provided with a dispensing device constructed in accordance with the invention which may be repeatedly used in connection with cans which are not provided with the dispensing spouts. The dispensing spouts previously referred to which were provided with the can or container were further objectionable in that their size was not sufficient to bring the same in close proximity to the filling opening of fuel tanks on motor vehicles and, consequently, considerable spillage and waste, as well as the danger incident thereto, was occasioned in the use of the former.

The dispensing device constituting the subject matter of the present invention consists of a flexible conduit 10, such as a length of canvas hose or its equivalent which is sufficiently long to permit of its introduction directly into the filling opening of a receiver when the device is associated with the container. The device further includes a hollow cylindrical member or tube 11 which is telescopically fitted within one end of the conduit 10 with a portion thereof protruding therefrom and formed to provide a pointed terminal 12 having diverging cutting edges 13. Preferably, the member 11 is tapered and is of gradually increasing diameter from the outer or free end to its opposite end or at least to the juncture of its protruding portion with the secured end of the conduit 10. In practice, suitable fastening means will preferably be provided, such as the fasteners 14 which are arranged in circumferentially spaced relation to extend through the conduit 10 and member 11. The secured end of the conduit 10 forms a shoulder 15 at the juncture thereof with the protruding portion of the member 11, and the protruding portion of the member 11 at this point is preferably provided with external threads 16, the purpose of which will be hereafter set forth. The protruding portion of the member 11 immediately beyond the threads 16 and slightly spaced from the shoulder 15 is provided with a circumferentially spaced series of openings 17.

In use and operation, the device is arranged in substantially the position illustrated in Figure 1 of the drawings with respect to the container or can B, and by exerting a rapid downward pressure on the device, it is obvious that the pointed terminal 12 will pierce the container while the diverging cutting edges 13 will function to perforate and remove therefrom and eject into the container a circular portion of the wall. When the attached end of the conduit 10 which constitutes the shoulder 15 abuts with the wall of the container, the portion of the member 11 provided with

the external threads 16 will establish a liquid tight seal with the wall of the opening thus formed, and by inverting or tilting the container B it is apparent that the contents will flow through the member 11 into the conduit. The opposite free end of the conduit may be positioned within the filling opening of a receiver, as clearly illustrated in Figure 3, so as to avoid spillage of the contents. The threaded portion 70 serves to lock the member 11 in the opening against accidental displacement, and it will be found in practice that in order to remove the member 11 from the opening, it is necessary to unscrew the threaded portion 75 from the opening to detach the device from the container. The opening 17 will serve as a means for completely draining the contents of the container so as to avoid leaving 80 of any appreciable amount therein which would entail a loss to the user. After the container B is emptied, the dispensing device is removed for subsequent use in connection with other containers. When not in use, the pointed terminal 12 and cutting 85 edges 13 may be protected against injury to the person or against dulling thereof by telescopically arranging the free opposite end of the conduit 10 over the protruding portion of the member 11, as illustrated in 90 Figure 5. This will also serve to prevent dust, dirt or other foreign matter from collecting within the conduit or member 11, as the free end of the conduit also covers the opening 17. The fastening devices 14, 95 in addition to securing the conduit and member 11 together, also serve to prevent any possibility of the removed portion of the container wall from passing through the member 11 into the conduit 10 and possibly 100 finding its way into the receiver.

In order to provide means for venting the interior of the conduit 11, to facilitate the flow of the liquid during the pouring operation, a vent 18 is formed in the conduit 110 at a point between the attached end or shoulder 15 and the inner end of the member 11. Suitable means is provided, such as the U-shaped element 19, for forming a passageway 20 between the conduit and the 115 member, which passageway leads from the venting opening 18 to the interior of the conduit beyond the member 11.

From the foregoing, it will thus be seen that an improved dispensing device has 120 been devised by virtue of which sealed containers may be opened and their contents dispensed or poured into a receiver without spillage or waste of the contents.

What is claimed is:

1. A dispensing device including a flexible conduit and a hollow cylindrical member fitted within one end of, secured to said conduit and protruding therefrom, said protruding end being cut to form a pointed ter- 125 130

5. **5** minal having diverging cutting edges for perforating a wall of, removing therefrom and ejecting into the container a circular portion of the wall to afford an outlet opening, the said cylindrical member being of gradually increasing diameters from its pointed terminal to its juncture with the conduit, whereby to snugly fit the outlet opening formed in the container, the attached end of the conduit presenting a shoulder for limiting the insertion of the member into the container.

10. **15** 2. A device adapted to be associated with a sealed container for dispensing its contents, said device including a flexible conduit, a hollow cylindrical member fitted within one end of said conduit and protruding therefrom, circumferentially spaced means extending through the member and 20 conduit for securing the same together, the protruding end being cut to form a pointed terminal having diverging cutting edges for perforating a wall of, removing therefrom and ejecting into the container a circular portion of the wall to provide an outlet opening, the said securing means also serving to prevent the removed portion of the wall from passing through the member into the conduit.

25. **30** 3. An attachable spout for containers comprising a tube having a portion adapted to be secured to the container, a conduit secured to the tube laterally of the portion to form a lapped joint, a portion of the lapping tube and conduit being spaced to form a passageway communicating at one end with the interior of the tube and at its opposite end opening exteriorly of the tube.

35. **40** 4. An attachable spout for containers comprising a tube having a portion adapted to be secured to the container, a conduit secured to the tube laterally of the portion to form a lapped joint, a section of the lapping tube and conduit being spaced longitudinally to form a passageway the end of which adjoining the portion opening exteriorly of the spout and the opposite end of which opening interiorly of the spout.

45. **50** Signed at 26 Broadway in the city and county of New York and State of New York this 6th day of June, 1929.

LAURITZ MARTIN NARBO.
